(57) **CLAIM**

The ornamental design for an automobile and/or toy replica thereof, as shown and described.

DESCRIPTION

FIG. 1 is a front perspective view of an automobile and/or toy replica thereof in accordance with my new design;

FIG. 2 is a front elevational view thereof;

FIG. 3 is a rear elevational view thereof;

FIG. 4 is a top plan view thereof; and,

FIG. 5 is a left side elevational view thereof.

The claimed design is directed to portions of the automobile and/or toy replica thereof which emit light when supplied with power.

The broken line showing on the automobile and/or toy replica thereof represents the boundary of the claimed design and forms no part of the claimed design. The lighter tones which surround the broken lines are included for illustrating the environment and form no part of the claimed design.

1 Claim, 5 Drawing Sheets
